UNITED STATES PATENT OFFICE.

HAROLD EGG, OF BILLINGSHURST, ENGLAND.

DEVICE FOR PRODUCING RELATIVE TRANSLATIONAL MOVEMENT.

Application filed April 20, 1921. Serial No. 462,954.

To all whom it may concern:

Be it known that I, HAROLD EGG, a subject of the King of Great Britain, residing in Billingshurst, England, have invented certain new and useful Improvements in Devices for Producing Relative Translational Movement, of which the following is a specification.

This invention relates to mechanical devices such as adjustable spanners, secateurs, bolts or the like in which it is desired to produce relative translational movement between two members of the device, such movement being effected by means of an operating handle or lever suitably correlated with these members by pivot and pin and slot connections, and it is to this correlation of the actuating handle or lever with the relatively movable members actuated thereby that the invention more particularly relates.

It will be convenient to refer to the two relatively movable members as the fixed member and the movable member respectively, but it will be understood that either may be regarded as the fixed member and the other as the movable member.

According to the present invention the actuating lever is correlated with what may be regarded as the fixed member by means of a pair of pin and slot connections, one slot being formed in the fixed member in the required direction of relative movement and the other slot in the actuating lever in a direction at right angles with the first mentioned slot or substantially so, and this double pin and slot connection between these two elements of the device is an essential feature of the present invention.

In the accompanying drawings Fig. 1 is an elevation partly in section of an automatically adjustable spanner embodying the invention; Fig. 2 is a side elevation of same; Fig. 3 a detached part elevation of the actuating lever; Fig. 4 an elevation with lever removed showing the remaining parts in another relative position; Figs. 5 and 6 detached elevations of the spanner jaws; and Fig. 7 a perspective view of a modification, this latter construction being particularly applicable to pliers and secateurs.

Referring first to Figs. 1-6, *a* and *b* are the two jaws of the spanner which have slots *a'*, *b'* respectively parallel with each other and with the direction of relative movement of the jaws. A pin *a*² carried by the mov-

able jaw *a* engages slot *b'* and a pin *b*² carried by the fixed jaw *b* engages slot *a'*. Additional guiding means for the relative movement are provided in a rib *a*³ on jaw *a* 60 sliding in a groove *b*³ in jaw *b*.

The actuating lever *c* is bifurcated at its head to embrace both jaws which are preferably suitably recessed to accommodate the forks of the lever flush with their outer faces and the pins *a*², *b*² pass through the forks, one of them, viz. pin *a*² in the drawings, fitting easily in circular holes *c*⁰ in the forks, and the other, viz. *b*² in the drawings, fitting easily into a slot *c'* in the forks running at right angles to the direction of the slots *a'*, *b'* in the jaws.

In the construction of Fig. 7 the fixed jaw *g* is formed with a slot *g'* extending in the direction of the required relative movement, 75 a pin *h*² passing through this slot and through holes in jaw *h* and in the embracing forks *i*⁰ in the head of the actuating lever *i*. The latter is correlated with the jaw *g* by means of a pin *g*² in a handle extension *g*⁰ 80 of the jaw *g* which engages a slot *i'* in the actuating lever, this slot being, as shown in the drawings, substantially at right angles to slot *g'*.

It will be obvious that many modifications 85 may be made, in accordance with the purpose to be served, in the actual construction of apparatus such as contemplated in the present invention without exceeding the scope thereof. For example, referring to 90 Fig. 7 the two members *g*, *h*, may be modified so that a horizontally projecting portion of the movable jaw would form the bolt or latch of a door. In the same way the members may be arranged so that this same 95 portion would form the lifting member of a jack.

Having thus described the nature of the said invention and the best means I know of carrying the same into practical effect, I 100 claim:—

1. In mechanical devices, such as adjustable spanners or the like in which it is desired to produce relative translational movement of two members of the device by means 105 of an actuating handle or lever, a double pin and slot connection correlating the actuating lever with one of the relatively movable members comprising a slot in said member aligned in the required direction of relative 110 motion and cooperating with a pin in the said lever, and a slot in the actuating handle

or lever aligned substantially at right angles to the slot in the aforesaid member and cooperating with a pin in said member, substantially as described.

- 5 2. An adjustable spanner or the like comprising two relatively movable jaws and an actuating lever, guiding means on the jaws, a pin fitting in aligned holes in the said lever and one jaw and passing through a slot in the second jaw and a pin in the latter jaw passing through a slot in the lever, said slot being aligned substantially at right angles to the first mentioned slot, substantially as described.
- 10 3. An adjustable spanner or the like, comprising two relatively movable jaws and an actuating lever, a pin fitting in aligned holes in said lever and one jaw and passing through a slot in the second jaw aligned in the required direction of relative motion, a
- 15

second pin carried by the second jaw and passing through slots in the first jaw and in the lever aligned at right angles to each other, substantially as described.

- 20 4. An adjustable spanner or the like, comprising two relatively movable jaws and an actuating lever correlated by pin and slot connections, guiding means on the jaws, a pin fitting in aligned holes in said lever and one jaw and passing through a slot in the second jaw parallel with aforesaid guiding means, a second pin carried by the second jaw and passing through a slot in the first jaw also parallel with said guiding means and through a slot in the lever at right angles to the other slots, substantially as described.

In testimony whereof I have signed my name to this specification.

HAROLD EGG.
